(No Model.)

W. C. TRUSSELL.
STREET CAR MOTOR.

No. 327,623.

Patented Oct. 6, 1885.

FIG. 2.

UNITED STATES PATENT OFFICE.

WILBURT C. TRUSSELL, OF BOSTON, MASSACHUSETTS.

STREET-CAR MOTOR.

SPECIFICATION forming part of Letters Patent No. 327,623, dated October 6, 1885.

Application filed February 16, 1885. Serial No. 156,105. (No model.)

To all whom it may concern:

Be it known that I, WILBURT C. TRUSSELL, a citizen of the United States, residing at Boston, in the county of Suffolk and State of Massachusetts, have invented a new and useful Improvement in Street-Car Motors, of which the following is a specification.

The object of my invention is to produce a simple and efficient arrangement of mechanism for propelling street-railway cars by manual power, thereby dispensing with horse or other power.

The invention consists in securing to each axle of the car a worm-wheel, either of which can be caused to rotate (according to the direction of the car) by means of a worm mounted upon one end of a shaft supported by suitable bearings under the car, which shaft is caused to rotate by means of a chain passing around a small sprocket-wheel on the outer end of the shaft and around a large sprocket-wheel mounted on a suitable frame on the platform of the car, the large sprocket-wheel being provided with a handle, so as to be turned by the driver of the car.

The invention further consists in the employment of a series of loose pulleys, around which the chain is passed for obtaining greater power; and suitable means for throwing the worm in and out of gear with the worm-wheel on the rear axle are also described.

Referring to the accompanying drawings, Figure 1 represents a longitudinal vertical section of a street-railway car embodying my invention. Fig. 2 is a transverse vertical section of the same, taken on line $\alpha\alpha$ of Fig. 1.

A represents a portion of a street-railway car, B the axle, and C the wheel. On the axle B is secured a worm-wheel, D, and in suitable bearings, $e\ e'$, secured to the under side of the car-floor is mounted a shaft, E, upon which is secured a worm, F, that gears with the worm-wheel D. On the outer end of the shaft E is mounted a small sprocket-wheel, G. To the platform of the car is secured a frame, H, in which is supported a large sprocket-wheel, I, and to the platform is also secured a standard, J, to which two loose pulleys, K and L, are secured. An endless chain, M, is passed over the large sprocket-wheel I and under the small sprocket-wheel G, then up and over the loose pulley K, and down under the loose pul-

ley L, then up to the large sprocket-wheel I, which is fitted with an adjustable handle, i .

The rear bearing, e , of the shaft E is free to slide in a dovetail groove in a block, f , secured to the bottom of the car, and is pushed backward or forward by means of a lever, N, shown in the drawings as passing up under the seat, but which may be made to pass out to the side of the car, so that when the bearing e is pushed back that end of the shaft will be raised and the worm F lifted out of gear with the worm-wheel D, and when again pushed forward will fall into gear with the same; but any other device for throwing the worm F in and out of gear with the worm-wheel D may be employed.

Upon turning the sprocket-wheel I by the handle i in the direction of the arrow marked 1 the chain M is drawn in the direction of the arrows marked 2 2, the chain on this side being always kept taut, while it is slightly slack on the opposite side, where the arrows are marked 3 3. Great power is obtained by the chain passing around the loose pulleys K L, as described, without any diminution of speed. The small sprocket-wheel G, and with it the shaft E, is thus caused to make several revolutions to one of the large sprocket-wheel I, 8 3 and for every revolution of the shaft E the worm F moves the worm-wheel D one tooth, so that if the worm-wheel D has twelve teeth, as shown, twelve revolutions of the shaft E will be required to revolve the wheel D once, 8 5 and should the proportions of the wheels I and G be as six to one, then the wheel C of the car will revolve once for every two revolutions of the wheel I.

When the car has arrived at the end of its 90 journey, the worm F is thrown out of gear with the worm-wheel D by means of the hand-lever N, and the other worm thrown into gear with the worm-wheel on the other axle, when the car will be ready to start in the opposite 95 direction.

For cars that are to work on level ground the chain M need only to pass around the large and small sprocket-wheels, thereby dispensing with the loose pulleys K and L and the standard J.

When it is desired to stop the car, the driver has only to leave off turning the handle i , and the worm F will prevent the worm-wheel D

from revolving, so that the usual brakes will not be required when the car is fitted with my invention.

What I claim as my invention is—

- 5 In combination with the axle of a street-railway car, the worm-wheel D, worm F, shaft E, sprocket-wheels G and I, and chain M, substantially as shown, and for the purposes described.

In testimony whereof I have signed my name to this specification in the presence of two subscribing witnesses.

WILBURT C. TRUSSELL.
